UNITED STATES PATENT OFFICE

100,588

DESIGN FOR A TOILET ACCESSORY CONTAINER

Eula Manes Stone, New York, N. Y.

Application May 9, 1935, Serial No. 56,762

Term of patent 14 years

To all whom it may concern:

Be it known that I, Eula Manes Stone, a citizen of the United States, residing at New York city, county of New York, Borough of Manhattan, and State of New York, have invented a new, original, and ornamental Design for a Toilet Accessory Container, of which the following is a specification, reference being made to the accompanying drawing, forming a part thereof.

I claim:—

The ornamental design for a toilet accessory container, as shown.

EULA MANES STONE.
